BUILDING PANEL

Roger A. Hield, Kansas City, Mo., assignor to Butler Manufacturing Company, Kansas City, Mo., a corporation of Missouri

Application February 14, 1955, Serial No. 34,502

Term of patent 14 years

(Cl. D54—2)

Fig. 1 is a perspective view of a building panel embodying my new design.

Fig. 2 is an end elevational view of same.

I claim:

The ornamental design for a building panel, substantially as shown.
